[57] CLAIM

The ornamental design for an automobile, as shown and described.

DESCRIPTION

FIG. 1 is a perspective view of an automobile showing our new design;

FIG. 2 is a side elevational view thereof;

FIG. 3 is an enlarged front perspective view thereof;

FIG. 4 is an enlarged rear perspective view thereof; and

FIG. 5 is a top perspective view thereof.

The side of the automobile opposite to that shown is substantially a mirror image thereof.
